Attorneys

UNITED STATES PATENT OFFICE.

- VIRGIL O. JONES, OF NANTIC, ILLINOIS, ASSIGNOR OF ONE-THIRD TO WILLIAM C. JONES, OF NANTIC, ILLINOIS, AND ONE-THIRD TO FRANK E. HARROLD, OF DECATUR, ILLINOIS.

OIL BURNER.

Application filed April 6, 1923. Serial No. 630,212.

To all whom it may concern:

Be it known that I, VIRGIL O. JONES, a citizen of the United States, a resident of Niantic, in the county of Macon and State of Illinois, have invented a certain new and useful Oil Burner, of which the following is a specification.

This invention relates to improvements in oil burners and the principal object of the invention is the provision of such a device which will operate efficiently and effectively to produce a maximum heat with a minimum consumption of oil, which may be readily and cheaply constructed and adjusted 10 and easily operated, having few parts, resulting in a minimum amount of wear and tear from operation.

Other objects of the invention include improvements in detail of construction and operation whereby a simple and efficient device of this kind is provided.

To the accomplishment of the foregoing and such other objects as hereinafter appear, my invention consists in the construction, 25 combination, and arrangement of parts hereinafter described and then sought to be defined in the appended claims, reference being had to the accompanying drawing forming a part hereof and which shows merely 30 for the purpose of illustrative disclosure a preferred embodiment of my invention, it being expressly understood, however, that various changes may be made in practice within the scope of the claims without digressing from my inventive idea.

In the drawing,—

Figure 1 represents a view in vertical cross section of a device constructed to embody my invention.

Figure 2 is a top plan view thereof, the pipes and the evaporating and reservoir chamber being eliminated to properly disclose the structure.

Referring now to the drawings, the numeral 1 designates the burner body or structure which is adapted to be suitably mounted and supported wherever it is to be used. This is in the form of a cylindrical chamber or compartment formed of a suitable casing 45 of metal and having the depending inlet pipe 2 leading thereto. This body is provided with a plurality of burner apertures 3 suitably arranged around the sides thereof and on top is provided with a suitable annular edge flange 4 and a centrally located an-

nular flange 5. It is further provided with a pair of parallel vertical flanges 6 to form a channel 7 having its ends closed as at 8 and spaced apart as at 9 to provide an entrance into the circle of said channel from the outer part of the top of the burner body. A plurality of burner holes or apertures 10 are provided through the top of the burner body and open within the annular flange 5, and another series of burner apertures 11 are provided through the top of the burner body opening into the channel 7. In addition suitable sockets 12 are provided on top of the burner body to receive the supporting pipes or rods 13 which securely support the 60 evaporating chamber and gas reservoir chamber in proper position.

The gas reservoir chamber is designated by the numeral 14 and in the form of a cylindrical compartment as shown, having the 75 laterally extending ears 15 which are apertured to receive the posts or rods 13 and provided with the screw or other suitable adjusting means 16 whereby the position of the gas reservoir chamber 14 and its connecting 80 evaporating chamber to be presently described may be properly fixed.

This fuel evaporating and gas forming chamber I designate by the reference numeral 17 and it is also in the form of a 85 cylindrical chamber or compartment and is connected to the gas reservoir chamber 14 by means of a suitable pipe or neck 18. The fuel evaporating and gas forming chamber is positioned directly over the central burner 90 apertures 10 as shown and is directly subjected to their heat. It is less in diameter than the gas reservoir chamber, the latter therefore being subjected to the transmitted 95 heat of the central burner apertures 10 and the direct heat of the other burner apertures 11 as indicated, and of course the heat of the latter also is applied to the fuel evaporating and gas forming chamber 17 as well. Pipe 19 is connected to the fuel evaporating 100 and gas forming chamber 17 and leads to the oil supply pipe 20, having the needle valve 21 interposed therein whereby the flow of fuel to the fuel evaporating and gas forming chamber may be readily regulated. A 105 branch pipe 22 controlled by a suitable valve 23 leads from the inlet pipe 20 to the top of the burner body or casing 1. This is for the purpose of supplying the oil or fuel thereto which will flow into the central part 110

of the top of the burner body or casing within the annular flange 6 whereby it may be ignited to initially heat the fuel evaporating and gas forming chamber 17 in starting the operation of the burner.

5 The gas outlet pipe 24 is connected to one end of the gas reservoir chamber 14 and is extended downwardly and into the air inlet pipe member 2 which leads into the bottom 10 of the burner body and has the gas inlet opening 25 for the purpose of supplying gas into the burner body.

With this description of the construction of this device its operation is readily apparent therefrom. The oil or other liquid fuel is suitably supplied to the fuel evaporating and gas forming chamber 17 where it is subjected to the heat from the burner as previously described and vaporized or 20 gasified, flowing to the reservoir chamber 14, from whence a suitable quantity of the gas flows through the discharge pipe 24 through its outlet 25 and into the main burner body or casing 1. A suitable quantity 25 of air for proper combustion is drawn in through the pipe 2 so that the burner body is filled with a proper mixture of air and gas for most efficient operation.

In order to give some idea of the method 30 of obtaining the proper dimensions, it is to be understood that one ounce of liquid fuel expands into 550 cubic inches of gas, and to burn one ounce of oil per minute, the gas reservoir chamber must be large enough 35 to handle 550 cubic inches of gas per minute, and the burner or combustion chamber must be large enough to handle a volume composed of 94% air and 6% gas. The gas combustion chamber must therefore have a 40 capacity of 51,700 cubic inches per minute. Of course these figures can be based on the per second consumption as well.

What I claim is:—

1. A device of the character described including, in combination, a combustion chamber and burner body having a plurality of burner apertures in the side thereof and a plurality of burner apertures located in the central part of the top thereof, a gas reservoir chamber and a fuel evaporating and gas forming chamber connected thereto, both of said chambers being supported above said combustion chamber and burner body in vertical spaced relation with the fuel evaporating and gas forming chamber between the gas reservoir and the burner body so that said fuel evaporating and gas forming chamber is subjected to the heat of the combustion at said central apertures, and a supply connection leading from said gas reservoir chamber to the gas inlet of the combustion chamber and burner body.

2. A device of the character described including, in combination, a combustion chamber and burner body cylindrical in shape and

having a combined air and gas inlet at the bottom thereof, said chamber also having an annular channel formed in the top thereof, having openings through the top of said chamber into said channel, and also having a cup-shaped compartment provided in the top thereof by means of an annular flange with openings extending through the top thereof within said flange, a fuel evaporating and gas forming chamber positioned 75 above said cup so that it will be subjected to the heat from the said last mentioned burner apertures, a gas reservoir chamber positioned above said last mentioned chamber in spaced relation with the same to cause 80 the flames to impinge against the top of the fuel evaporating and gas forming chamber and communicating therewith and arranged so as to be subjected directly to the heat from said apertures in said channel, and a connection leading from said gas reservoir chamber to said combined air and gas inlet.

3. A device of the character described including, in combination, a combustion chamber and burner body cylindrical in shape 90 and having a combined air and gas inlet at the bottom thereof, said chamber also having an annular channel formed in the top thereof, having openings through the top of said chamber into said channel, and also having a cup-shaped compartment provided in the top thereof by means of an annular flange with openings extending through the top thereof within said flange, a fuel evaporating and gas forming chamber positioned 100 above said cup so that it will be subjected to the heat from the said last mentioned burner apertures, a gas reservoir chamber positioned above said last mentioned chamber and communicating therewith and arranged so as to be subjected directly to the heat from said apertures in said channel and arranged to cause the flames to impinge 105 against the top of the fuel evaporating and gas forming chamber, a connection leading 110 from said gas reservoir chamber to said combined air and gas inlet, a fuel supply connection for said fuel evaporating and gas forming chamber, and means for supplying fuel to the top of said burner body 115 for starting the combustion.

4. A device of the character described including, in combination, a combustion chamber and burner body cylindrical in shape and having a combined air and gas inlet at 120 the bottom thereof, said chamber also having an annular channel formed in the top thereof, having openings through the top of said chamber into said channel, and also having a cup-shaped compartment provided 125 in the top thereof by means of an annular flange with openings extending through the top thereof within said flange, a fuel evaporating and gas forming chamber positioned above said cup so that it will be subjected to 130

the heat from the said last mentioned burner apertures, a gas reservoir chamber positioned above said last mentioned chamber and spaced therefrom and communicating therewith and extending beyond the same so as to be subjected directly to the heat from said apertures in said channel and also to cause the flames to impinge against the top of the fuel evaporating and gas forming chamber, a connection leading from said gas reservoir chamber to said combined air and gas inlet, and supporting means for adjustably supporting said two last mentioned members on said burner body.

5 5. A device of the character described including, in combination, a combustion chamber and burner body cylindrical in shape having a combined gas and air inlet leading into the bottom thereof and having a plurality of burner apertures around the sides thereof and also provided with a centrally located group of burner apertures and also an annular group of burner apertures through the top thereof, a plurality of supports extending upwardly from said burner

10 15 20 25

body, a gas reservoir chamber in the form of a cylindrical compartment having a plurality of apertured ears to receive said supports whereby it is supported above said burner body and subjected to the direct heat of combustion at said annular series of said burner apertures, a fuel evaporating and gas forming chamber communicating with and supported below said gas reservoir chamber so as to be subjected to the direct heat of said central group of burner apertures and being of a diameter less than the diameter of the gas reservoir chamber whereby the latter is adapted to cause the flames to impinge against the top of the fuel evaporating and gas forming chamber, a discharge connection leading from said gas reservoir to the combined air and gas inlet of the combustion chamber and burner body, and a fuel supply connection to said fuel evaporating and gas forming compartment.

In testimony that I claim the foregoing, I have hereunto set my hand this 26 day of March, 1923.

VIRGIL O. JONES.
